HAMMOCK

Harry Robertson Dillon, Richmond, Va.

Application December 18, 1942, Serial No. 469,740

7 Claims. (Cl. 5—122)

This invention relates to hammocks and the like constructed in a network manner.

One of the objects of this invention is the provision of a hammock provided with a plurality of links interlocked in such a manner as to retard raveling and limit actuation of said links.

Another object of this invention is the provision of an adjustable hammock.

A further object of this invention is the provision of a plurality of links, bands, circles or loops secured to one another and interwoven so as to form a network for hammocks.

A still further object is the method of securing together a plurality of links or loops to form a material for use in connection with a hammock or other useful articles.

Other objects and features will more fully appear from the following description and accompanying drawings, in which:

Fig. 1 is a top plane broken view of the invention; Fig 2 a distorted schematic top plan view; Fig. 3 a transverse cross sectional view taken along lines 3—3 of Fig. 2 and Fig. 4 a transverse cross sectional view along lines 4—4 of Fig. 2.

Referring to the drawings a hammock 1 consists of a head bar 2 to which are respectively secured guy lines 3—4 that pass through a foot bar 5 and are secured by cleats 6 to a ring 7.

The body or bed 8 of the hammock consists of a plurality of longitudinal and transverse or warp and woof members 9—10 respectively comprised of links interlocked with one another as hereinafter more fully explained.

The longitudinal and transverse members consist of links interlocked in series fashion. The links are preferably constructed of flexible material such as twine, cord or the like.

The body of the hammock is constructed as follows: a plurality of longitudinal links 12 are respectively secured to the head bar and respectively held in spaced relation to one another by filler links 13. Longitudinal links 14 are respectively interlocked with links 12 and links 15 with links 14 and so on throughout the desired length of the body.

Links 12 and filler links 13 are limited in movement by a series of lock links 16, etc., as follows: lock link 16 is secured to guy line 3 and registers with filler link 13. Lock link 17 (see Fig. 3) interlocks link 16 and filler link 13 and this interlocking method is continued throughout the desired width of the body.

Referring to Figs. 2 and 4 the transverse members 10 are constructed as follows: Link 18 is secured to guy line 3 and interlocks with link 19

and such interlocking method is continued throughout the desired width of the body. Transverse members are secured to guy line 4 by turning end link 20 so as to form an eyelet through which guy line 4 is passed to provide securing means of said transverse members.

It is to be understood that the transverse members are held in spaced relation by filler links and secured in similar fashion as the longitudinal members hereinbefore more fully described.

It is obvious from the foregoing and the following that both transverse and longitudinal locking links limit movement of said transverse and longitudinal members, for instance, the links when interlocked with each other assume a substantial triangular shape; each having a central opening or aperture through which the longitudinal or transverse members may be disposed. Thus, link 19 (Fig. 2) of transverse member 10, is disposed in the central opening of link 15 of longitudinal member 9; while link 15 of the adjacent longitudinal member 9 is disposed in the central opening of the link adjacent to link 19 of the transverse member 10. Therefore, when the longitudinal or transverse members pass through the links in alternative fashion their lateral movement is limited; as is obvious from Figs. 2—3—4.

It is also obvious from the foregoing description and accompanying drawings that the longitudinal and transverse members alternatively and respectively pass over and through one another so as to provide a substantial continuous interlocking means which tends to prevent raveling.

A plurality of clews or cords 21 pass through a ring 22 and are secured to said head bar, and thereby provides a self-adjusting feature (see Fig. 2) since said clews may be lengthened or shortened with respect to said head bar and ring.

Referring to Fig. 1 the longitudinal members and locking members 23 are secured as follows: End links 24 of said longitudinal and locking members are grouped together in a desired number and turned so as to provide eyelets through

which passes a continuous adjustable clew or cord 26 secured in ring 7. Adjustable means 25 consists of links disposed upon and slideable on clew 26 and are provided to lengthen or shorten said body with respect to said ring and end of said longitudinal and locking members.

It is to be understood that the foregoing description is one method of constructing the device and applicant is not to be limited in other methods substantially employed within the scope of his invention.

It is understood that the basic links may be made of any material.

It is to be further understood that the method used in the interlocking of links may be employed in similar fashion in the construction of bath mats, cushions, drapes, sacking, hosiery, and metallic articles, such as netting and the like.

Having described this invention, what is claimed is:

1. A device of the character described consisting of a plurality of longitudinal members respectively formed of links interlocked with each other in series fashion; each link having a central opening; a plurality of transverse members respectively formed of links interlocked with each other in series fashion and each link having a central opening; said longitudinal members respectively passing over and through said transverse members in alternative fashion, and said transverse members respectively passing over and through said longitudinal members in alternative fashion.

2. A device of the character described consisting of a plurality of longitudinal apertured members; a plurality of transverse apertured members; said longitudinal members respectively passing about and through the apertures of said transverse members; said transverse members respectively passing about and through the apertures of said longitudinal members in alternate manner, and elongated members to which the ends of said longitudinal and transverse members are secured.

3. A device of the character described consisting of a plurality of apertured longitudinal members each having one of its ends secured to a head bar, and the other of its ends secured to means engaging a ring; said means being held in spaced relation by a foot bar; a plurality of transverse apertured members each having its ends secured to respective guy lines connecting said head bar, foot bar and ring; said longitudinal and transverse members respectively passing over and through the apertures of transverse and longitudinal members in alternate fashion, and means for suspending said head bar.

4. In a device of the character described, a plurality of links, each having its ends apertured, and being folded upon itself to form arms and a bight portion, each bight portion passing through the apertures of the next succeeding link to form a plurality of chain-like warp and woof members, said members being interwoven so that succeeding links of a first warp member pass alternately about and between the arms of a first row

5 of links consecutive woof members, while the second or next succeeding warp member has its links passing alternately between and about the next succeeding row of corresponding links of said woof members, the construction being repeated to form a woven structure of any desired extent.

10 5. In a device of the character described, a plurality of warp and woof members, each member comprising a plurality of links, each link having an aperture adjacent each end and being folded upon itself to form a bight and substantially parallel arms, each bight passing through the superposed apertures of the next succeeding link, to form a chain-like member, said members being interwoven so that regularly-recurring links of each warp member, pass between the arms of respective links in a corresponding row of links of said woof members, while the remaining links of said warp members have the corresponding links 15 20 of the respective woof members, passing between their arms.

25 6. In a structure of the character described, first and second warp members, first and second woof members, each of said members comprising 30 a series of links, each link comprising a length of material looped at its ends and folded upon itself to form a bight and superposed loop portions, each bight passing through the loops of the next succeeding link, to form a chain-like member, 35 one link of said first warp member passing between said loop portions of one link of said first woof member, the next succeeding link of said first warp member having its said portions passing on opposite sides of a link of said second woof member, and one link of said second warp member having its said portions passing on opposite sides of the next succeeding link of said first woof member, the next succeeding link of said second warp member passing between the parallel portions 40 45 of the next succeeding link of said second woof member, said construction being repeated to form a woven structure of any extent desired.

7. In a device of the character described, a plurality of links, each link having its ends apertured 50 and being bent upon itself to form a bight portion and superposed arms, each bight portion passing through the apertures of the next succeeding link to form warp and woof members, said members being interengaged so that alternate links of each warp member, pass between and about a corresponding row of links of said woof members, the construction being repeated to form a woven structure of any desired extent.

HARRY ROBERTSON DILLON.
